PORTABLE HANGING VANITY CASE

Filed Dec. 12, 1923

INVENTOR
Pasquale Mosonillo

BY
John J. Pechay
ATTORNEY

Patented Dec. 16, 1924.

UNITED STATES PATENT OFFICE.

PASQUALE MOSONILLO, OF BROOKLYN, NEW YORK.

PORTABLE HANGING VANITY CASE.

Application filed December 12, 1923. Serial No. 680,079.

To all whom it may concern:

Be it known that I, PASQUALE MOSONILLO, citizen of the United States, residing at Brooklyn, in the county of Kings and State 5 of New York, have invented certain new and useful Improvements in Portable Hanging Vanity Cases, of which the following is a specification.

This invention relates generally to vanity cases such as are used by women to carry cosmetics, face powder, or like toilet articles, the invention having for an object to provide a novel form of vanity case intended more particularly to be hung in automobiles, or on 10 walls generally if desired, a further specific object relating to a means for maintaining bottles containing perfume or the like in an upright position as the body of the case is swung between vertical and horizontal positions.

For further comprehension of the invention, and of the objects and advantages thereof, reference will be had to the following description and accompanying drawing, 15 and to the appended claims in which the various novel features of the invention are more particularly set forth.

Fig. 1 of the drawing is a perspective view showing my improved vanity case in open 20 position.

Fig. 2 is a fragmentary longitudinal sectional view taken on the plane indicated by the line 2—2 on Fig. 1.

Fig. 3 is a fragmentary longitudinal sectional view showing the vanity case closed.

As here embodied my improved vanity case comprises a shallow flat body member 10 to which is hinged at one end as at 11 a cover 12 having a depending peripheral 25 flange 12'. Inside this cover a mirror 14 may be mounted. The case may be of plain configuration or may be given any ornamental configuration that may be desired, the case here shown being of generally rectangular outline with oblique corners. The 30 mirror may be secured in place by a strap 14' which extends around inside the cover 12, the ends of the strap abutting and having a sleeve 14^a slipped thereover to hold the 35 two ends in position. Formed in the cover 40 are a number of holes 16 to receive screws whereby the device may be attached to a wall or surface on which it is desired to mount the case. As set forth above the device is 45 particularly suitable for mounting in an automobile.

The body element is swung down to the horizontal position shown in Fig. 1 when the case is to be used, being retained in this position by a pair of links 17, 18 connected to the respective cover and body elements and to each other and which collapse upon one another when the case is closed, and part 14^a being formed in the strap 141 to allow these links to fold into the cover. To close the 50 case the body element 10 is swung upward to a vertical position, and it may be held in this position by means of a suitable fastening element, that here shown consisting of a ball 19 on the cover which is adapted to snap 55 into a loop 20 on the body member 10.

Upon this body member 10, I mount a number of containers adapted to contain various toilet accessories, as here shown a pair of circular receptacles 23 which may be 60 utilized, contain rouge and powder, and an elongated receptacle 24 which may be utilized to contain a lip stick or the like. These receptacles may be closed respectively by 65 covers 25, and 26 which are provided with handles 27. In addition to the above elements, which are located toward the end of the body member removed from the hinge 11, I mount on the said body member, near the hinge end thereof, a pair of receptacles 30 70 which are adapted to have seated therein bottles 31 which may contain perfume or the like. These receptacles are aligned with one another transversely of the case, and are rigidly united to one another by the flat 75 strip 32 and the pin 33, the complete unit thus formed being hinged in the case by means of the hinge pintles 34 which are fixed at one end in the side wall of the casting and engage freely at their opposite ends 80 in sleeves 35 fixed to the sides of the receptacles in which the said pins engage freely. The hinge axis of the receptacles is located, as will be noted, adjacent the lower corner 85 of the latter and away from the near, or hinge end of the case so that these receptacles may be swung to a position to cause the bottles to lie flat against the main bottom 90 wall of the body member when the latter is raised to close the case, the bottles thus 95 maintaining their upright positions at all 100 times.

To accomplish this I fix to the link 18 which latter is hinged at its lower end to the side of the body member at a point offset 110 from the pivot of the receptacles 30 a pin 38 which extends across the face of one of

the receptacles and between the latter and a flat spring 39 extending up the face of the receptacle this spring being here shown as of U-form with its legs straddling the wall of the receptacle and the leg on the inner face of said wall being attached thereto, the spring extending a short distance above the wall of the receptacle to permit of the pin moving upward above said wall when the case is being closed. The spring 39 is of sufficient strength to cause the pin 38 to be maintained in close relation to the wall of the receptacle as the body member swings upward so that receptacles 25 will be caused to swing on their pivot axis and maintain a substantially upright position. At the end of the closing movement the pin 38 moves above the wall of the receptacles 30, allowing the latter to swing close against the bottom of the casing, which now faces outward.

While I have illustrated and described a preferred embodiment of my invention it is to be understood that I do not limit myself to the precise construction herein set forth and that various changes and modifications might be made therein by me, without departing from the spirit and scope of the invention as defined in the appended claims.

Having thus described my invention what I claim as new and desire to protect by Letters Patent of the United States is as follows:

1. A vanity case comprising a body member, a cover hinged thereto, a receptacle for a liquid hinged to said body member, a pair of collapsible links connecting the cover and body member and limiting the opening movement of the cover, and means adapted for operation by said links to angularly adjust the said receptacle upon the said body member when the cover is swung on the latter.

2. A vanity case comprising a body mem-

ber, a cover hinged thereto, a number of receptacles for toilet preparations on said body member, certain of said receptacles being hinged to said body member to permit of angular adjustment with respect to the latter, and means adapted to be operated by swinging movement of the cover and to have a differential movement with respect to the latter to angularly adjust the said receptacles upon the said body member.

3. A vanity case comprising a body member, a cover hinged thereto, a receptacle for a liquid container hinged to said body, said cover being adapted to be suspended in upright position, a pair of collapsible links connecting the cover and body member whereby the latter may be held in horizontal position with the case open, and a pin projected from one of said links and adapted to engage the said receptacle to impart swinging movement relatively to the body member to said receptacle as the body member is swung upon the cover.

4. A vanity case comprising a body member, a cover hinged thereto, a receptacle for a liquid container hinged to said body, said cover being adapted to be suspended in upright position, a pair of collapsible links connecting the cover and body member whereby the latter may be held in horizontal position with the case open, and a pin projected from one of said links and adapted to engage the said receptacle to impart swinging movement relatively to the body member to said receptacle as the body member is swung upon the cover, and a flat spring fixed to said receptacle and acting to retain the said pin in engagement with the receptacle.

In testimony whereof I have affixed signature.

PASQUALE MOSONILLO.
